(Cl. D58—26)

To all whom it may concern:

Be it known, that I, Hugo Bell, a citizen of the United States, residing at Wilton, Connecticut, have invented a new, original, and ornamental Design for a Combined Perfume Bottle and Holder Therefor or Similar Article, of which the following is a specification, reference being had to the accompanying drawing, forming a part thereof.

Fig. 1 is a plan view of a combined perfume bottle and holder therefor or similar article, showing my new design.

Fig. 2 is an end elevational view thereof.

Fig. 3 is a perspective view thereof.

I claim:

The ornamental design for a combined per-

fume bottle and holder therefor or similar article, substantially as shown.

HUGO BELL.
